UNITED STATES PATENT OFFICE

142,056

DESIGN FOR A PICTURE FRAME

Albert Barrett, Elmhurst, N. Y., assignor to
Reynolds Metals Company, Richmond, Va., a
corporation of Delaware

Application January 18, 1944, Serial No. 112,258

Term of patent 7 years

(Cl. D29—20)

To all whom it may concern:

Be it known that I, Albert Barrett, a citizen of the United States, residing at Elmhurst, in the county of Queens, Long Island, and State of New York, have invented a new, original, and ornamental Design for a Picture Frame, of which the following is a specification, reference being had to the accompanying drawing, forming part thereof, and in which:

Figure 1 is an elevational view of the picture frame showing my new design.

Figure 2 is a horizontal sectional view of the

frame on the line 2—2 of Figure 1, in the direction of the arrows.

The essential features of my design reside in the contrasting opaque and transparent areas, the transparent picture cover extending beyond the outer edge of the opaque border, substantially as shown.

I claim:

The ornamental design for a picture frame, substantially as shown and described.

ALBERT BARRETT.
